GLOW-DISCHARGE TUBE

Willem Six, Eindhoven, Netherlands, assignor to Hartford National Bank and Trust Company, Hartford, Conn., as trustee

Application July 5, 1952, Serial No. 297,278

Claims priority, application Netherlands August 17, 1951

3 Claims. (Cl. 313—190)

This invention relates to multiple position glow-discharge tubes for use in switching devices, more particularly for use in automatic telephone systems, in which a line of a first group is to be connected to a line of a second group and in which the electrodes associated with the lines of one group are formed by straight rods, arranged at regular intervals on a cylindrical surface, the electrodes associated with the lines of the other group being formed by identical, coaxial rings, which are coaxial to the said cylindrical surface.

Such tubes are known, but the ignition voltages of the various discharge paths formed at the crossings of the electrode groups may be different, since the intervals between the electrodes increase or decrease from one end of a group to the other. Such an arrangement is rather complicated, particularly with regard to the required screening between the discharge paths.

It is also known to provide auxiliary anodes in simple glow-discharge tubes for switching purposes, the ignition pulses being supplied to these auxiliary anodes.

The present invention has for its object to provide multiple glow-discharge tubes comprising auxiliary anodes for switching purposes, in which the discharges do not adversely affect the switching elements connected to the auxiliary anodes.

According to the invention, a multiple glow-discharge tube for switching purposes, in which one group of electrodes is formed by a number of rods, arranged at regular intervals on a cylindrical surface and the other group of electrodes is formed by a number of cylindrical rings of equal diameters and coaxial to the said cylindrical surface, the discharge paths formed at the crossings of the two electrodes groups being screened from one another by screens of insulating material formed by flat discs between the cylindrical rings and by elongated screens in meridian planes of the cylindrical surface, comprises auxiliary anodes parallel to the anodes and spaced apart by a small distance from the cathode at the side of indents in the cathode.

The main discharge concentrates in the indent in the cathode concerned, so that the auxiliary anode is not located in the direct discharge path and hence does not assume the potential of this discharge. This would have the disadvantage that the potential of the auxiliary anode with respect to the other cathodes would exceed the ignition voltage.

In order that the invention may be readily carried into effect, two examples will now be described in detail with reference to the accompanying drawings, in which:

Fig. 1 is a sectional view at right angles to the axis of a tube according to the invention, in which the screening is formed by mica plates;

Fig. 2 is a sectional view through the axis of the tube of Fig. 1 and

Figs. 3 and 4 show another embodiment, in which the screening is formed by ceramic plates.

Referring now to Figs. 1 and 2, reference numeral 1 designates the glass cylindrical tube wall. The tube contains a number of flat mica discs 2, having a comparatively large hole in the centre. Between the mica plates provision is made of comparatively low nickel rings 3, which constitute the cathodes. The cathodes, of which there are 10, are provided each with ten indents 4. Elongated mica strips 5, of which there are also 10, engage the mica discs 2 with the uses of recesses and are arranged so that they are located on each side of the indents 4 in the cathodes 3. Opposite the indents 4 are

the thick anode rods 6 and on each side thereof the thin auxiliary anode rods 7. The supply wires for the ten cathodes, designated by 8, extend through the holes in the rings 2 (Fig. 2 shows only the supply wires 8 of the upper and the lower cathode ring). The tube is filled with argon at a pressure of 15 mm. Hg. The spacing between the anode rods and the cathode rings is 3 mm., that between the auxiliary anodes 0.3 mm. The ignition voltage of the main discharge path is about 180 v. without auxiliary current. During operation the auxiliary current is a few tens of μ amperes. The running voltage of the main discharge path is 60 v. with a current of 6 m. amps. The ignition voltage of the auxiliary discharge is 70 to 75 v.

Referring to Figs. 3 and 4, reference numeral 1 designates the glass tube wall. The cathode rods are designated by 9 and the anode rings by 10. The wire-shaped auxiliary anodes are designated by 11 they have supply wires 12, to which they are connected by short wire connections 13. The ceramic screening plates have ten partitions 15 on the upper and the lower side, provided with recesses to accommodate the main anodes and the auxiliary anodes. The cathodes have indents 16 at the sides of the auxiliary anodes.

Although, owing to the more expensive manufacture, the embodiment shown in Figs. 3 and 4, enters into consideration only for greater series of tubes, this embodiment has the advantage that the electrodes may be stronger than those shown in Figs. 1 and 2, more particularly, since the anodes are held by the grooves in the ceramic plates.

What I claim is:

1. A multiple glow discharge tube comprising a group of cathode and a group of anode electrodes between which discharges are produced, one of said groups comprising a plurality of regularly-spaced rods defining a cylindrical surface, the other of said groups comprising a plurality of equal-diameter cylindrical rings arranged coaxially with respect to said cylindrical surface, insulating members for screening the discharges from one another comprising a plurality of flat discs disposed between the cylindrical rings and a plurality of elongated plates extending between the rods along meridian planes of the cylindrical surface, said cathode electrodes having indents on the side thereof facing the anode electrodes for concentrating the discharge thereat, and a plurality of auxiliary anodes extending parallel to the anode electrodes and slightly spaced apart from the cathode electrodes at the side of the indents for initiating discharges between the cathode and anode electrodes.

2. A multiple glow discharge tube comprising a group of cathode and a group of anode electrodes between which discharges are produced, said anode electrodes comprising a plurality of regularly-spaced rods defining a cylindrical surface, said cathode electrodes comprising a plurality of equal-diameter cylindrical rings arranged coaxially with respect to said cylindrical surface, insulating members for screening the discharges from one another comprising a plurality of flat discs disposed between the cylindrical rings and a plurality of elongated plates extending between the rods along meridian planes of the cylindrical surface, said cathode electrodes having indents on the side thereof facing the anode electrodes for concentrating the discharge thereat, and a plurality of auxiliary anode rods extending parallel to the anode electrodes at the side of the indents for initiating discharges between the cathode and anode electrodes.

3. A multiple glow discharge tube comprising a group of cathode and a group of anode electrodes between which discharges are produced, said cathode electrodes comprising a plurality of regularly-spaced rods defining a cylindrical surface, said anode electrodes comprising a plurality of equal-diameter cylindrical rings arranged coaxially with respect to said cylindrical surface, insulating members for screening the discharges from one another comprising a plurality of flat discs disposed between the cylindrical rings and a plurality of elongated plates extending between the rods along meridian planes of the cylindrical surface, said cathode electrodes having indents on the side thereof facing the anode electrodes

for concentrating the discharge thereat, and a plurality of auxiliary circular rods extending parallel to the anode electrodes and slightly spaced apart from the cathode electrodes at the side of the indents for initiating discharges between the cathode and anode electrodes.
